COMBINATION RECEPTACLE AND DISPENSING CABINET

Paul H. Horwitt, Hartsdale, N. Y.

Application December 23, 1932, Serial No. 648,656

2 Claims. (Cl. 206—16)

This invention relates to a combination receptacle and dispensing cabinet and has for an object to provide a cabinet that will act as a razor blade accessory, the cabinet having a dispensing holder for razor blade wipers or towels of the general nature shown in Patent No. 1,967,937 and a removable receptacle for depositing old razor blades.

A further object of this invention is to provide a combination cabinet that may be easily attached in the bathroom of the home or of a hotel room or in the wash room of a Pullman car or the like. When used in a public place as in a Pullman car wash room an old razor blade receptacle may be periodically removed and emptied of old razor blades by the attendant such as a Pullman porter.

A further object of this invention is to provide a combination receptacle which may be easily attached between the washstand and the shaving mirror in the wash room making the same convenient for dispensing razor blade wipers or towels and for disposing of old razor blades.

With the foregoing and other objects in view, as will hereinafter become apparent, this invention comprises the constructions, combination and arrangements of parts, hereinafter set forth, disclosed and shown on the accompanying drawing. In this drawing,

Figure 1 is a view of a wash room having the cabinet comprising this invention in position therein,

Figure 2 is a front elevational view of the dispensing cabinet and old razor blade receptacle constituting this invention,

Figure 3 is a side plan view of Figure 2,

Figure 4 is a perspective view of the lower end of the cabinet with the old razor blade receptacle in partly removed position,

Figure 5 is a plan view of the back of the cabinet,

Figure 6 is a perspective view from the back of the old razor blade receptacle, and

Figure 7 is a view on line 7—7 of Figure 1.

There is shown at 10 the combination razor blade towel dispensing cabinet, and old razor blade receptacle comprising this invention which, as shown in Figure 1, in operative position will 50 preferably be mounted on the wall of a washroom above the washstand 11 and below the shaving mirror 12 or in other similar convenient positions. This cabinet comprises a dispensing cabinet 13 for razor blade towels or wipers and 55 an old razor blade holder or receptacle 14 mount-

ed below the towel dispenser 13, both being secured on a frame or mount 15.

Each of these three elements, the dispensing cabinet 13, the receptacle or holder 14, and the frame 15 will preferably be made from pressed metal although any other suitable material may be used. The dispensing cabinet 13 is secured to the frame or mount 15 by a plurality of prongs 16 integral with and projecting from the side and bottom walls of the receptacle 14, the prongs 16 being passed through appropriately placed apertures in the frame or mount 15 and bent over as shown in Figures 5 and 7. The bottom wall 17 of the dispensing cabinet 13 is preferably inclined as shown in Figures 3 and 6, while the front wall 18 is cut away as at 19 there being no top wall, while the frame 15 provides the rear wall.

This dispensing cabinet 13 is especially intended for holding and dispensing the razor blade wipers or towels, the razor blade wipers or towels being formed of specially prepared soft and absorbent paper folded into booklet form through which the razor is inserted or pulled through for wiping and cleansing. An example of one form of such wiper or towel is disclosed and claimed in Patent No. 1,967,937. As will be observed, the prongs 16 on the opposite side walls are bent in opposite directions while the prongs 16 on the lower wall 17 are bent upwardly, thus holding the receptacle 13 permanently in position on the frame or mount 15. Old razor blade holder 14 consists of a closed receptacle having a receptacle slot 20 formed in the inclined front 21 thereof permitting old razor blades to be dropped into the receptacle therethrough. A back wall 22 is secured to the receptacle front 21 by a plurality of prongs 23 passing therethrough and bent over in opposite directions.

This back wall 22 has a large slot 24 therein so that the old razor blades may be removed therefrom for permanent disposition, as by the attendant or Pullman porter when in use in a public wash room, who will do so periodically. The back 22 of the receptacle 14 has a pair of upwardly projecting tabs 25, these tabs 25 being passed through appropriately placed apertures 26 in the mount or frame 15. At the bottom or the mount or frame 15 a spring tab 27 is riveted thereto as at 28, the spring tab 27 having a bent lip 29 projecting through an appropriate aperture in the frame or mount 15. When it is desired to remove the receptacle 14 in order to dispose of the old razor blades therein the receptacle

14 is grasped firmly in the hand and pulled away from the bottom, thereby pulling the bottom of the back 22 past the spring lip 29 and allowing the prongs 25 to be removed from the aperture 26. 5
5 The old razor blades are then disposed of through the apertures 24 in the rear wall 22 and to replace the receptacle the prongs 25 are inserted through the apertures 26 and the bottom of the receptacle 14 is pressed down against the 10 spring lip 29 until the back 22 snaps past the spring lip 29 holding it firmly in position. In combination this receptacle and dispensing cabinet 10 is mounted on the wall of a wash room at any suitable securing means such as a nail or screw 15 through the apertures 30 and 31 provided in the frame or mount 15. The dispensing cabinet 13 will be kept filled with suitable razor blade wipers or towels allowing the user to help himself to a suitable towel through the open top and openings 19 in the front 18 of the cabinet. 20

When the user wishes to dispose of the razor blades, he merely drops his old safety razor blade through the aperture 20 into the receptacle 14. The Pullman porter or attendant will periodically remove receptacle 14 and empty it through the rear slot 24 and at the same time refill the dispensing cabinet 13, thus keeping this device in condition for continuous use. This invention, while useful in the home, is especially useful in 25 public places such as hotel rooms, or Pullman car wash rooms, for by providing razor blade wipers or towels in the dispensing cabinet 13, the hotel or Pullman car prevents the probability of the razor blade being wiped on towels thereby 30 ruining the towels, and further prevents the liability of old razor blades being mixed with dirty towels to the probable serious injury of the laundry attendant. While it is true that Pullman cars do provide slots in the car walls to receive old razor blades these slots are generally so 35 inconspicuous that they are often not used, but with this invention the receptacle is placed in such a position that it is forcibly brought to the attention of the user, being in front of him throughout the shaving process so that he will 40 naturally and obviously dispose of his old blade 45

in the receptacle when he has an old blade to dispose of.

The novel features and the operation of this device will be apparent from the foregoing description. While the device has been shown and the structure described in detail, it is obvious that this is not to be considered limited to the exact form disclosed, and that changes may be made therein within the scope of what is claimed without departing from the spirit of the invention. 10 15

Having thus set forth and disclosed the nature of this invention, what is claimed is:

1. A holder for paper wipers and used blades characterized by a support and a compartment for said blades secured to the support, the lower portion of the support having an area surrounded by an annular member raised above the plane of the support and constituting a frame for said area, cooperative securing means on said compartment and said frame, said securing means comprising a pair of spaced upwardly projecting prongs on the rear of the compartment, a pair of similarly spaced prong receiving slots in said frame, a forwardly projecting spring lip attached to the support within said area and a cooperating second lip secured to the rear of the compartment, said lips arranged to cooperate for locking the compartment to the support over and spaced from said area when the prongs are inserted in the receiving slots in said frame. 20 25

2. A holder for paper wipers and used blades characterized by a support and a compartment for said blades secured to the support, the lower portion of the support having an area surrounded by an annular member raised above the plane of the support and constituting a frame for said area, detachable securing means on said compartment and said frame, said securing means comprising cooperating elements on the rear of said compartment and in said frame, a forwardly projecting member attached to the support within said area and a cooperating second member secured to the compartment, whereby said compartment may be detachably positioned on the support over the area defined by said frame. 30 35 40 45
